UNITED STATES PATENT OFFICE

2,020,173

COMBUSTION APPARATUS

Frank A. Chambers and Charles F. McGinley,
Chicago, Ill.

Application October 2, 1931, Serial No. 566,526

2 Claims. (Cl. 230—95)

The invention relates to devices for producing efficient combustion of the fuel in boilers and for abating smoke.

One object of the invention is to provide improved and efficient means for producing substantially complete combustion of the fuel in boilers which is adapted for use in different types of boilers.

Another object of the invention is to provide improved means for delivering hot air and steam into the firebox in such a manner as to cause substantially complete combustion of the fuel.

Another object of the invention is to provide improved means for delivering hot air and steam into the firebox which can be easily installed in existing boilers of different types.

Another object of the invention is to provide improved means, for delivering air and steam into the firebox of the boiler to cause substantially complete combustion of the fuel, in which the mixing head with a steam nozzle and induction port is adjustable to produce the maximum efficiency with the minimum steam supply under varying conditions.

Another object of the invention is to provide improved means for delivering air and steam into the firebox in which the steam jet is disposed in an elbow of an air pipe to muffle the noise produced by the steam and the induced air.

Other objects will appear from the description.

The invention consists in the several novel features hereinafter set forth and more particularly defined by claims at the conclusion hereof.

In the drawing: Fig. 1 is a longitudinal section of a boiler embodying the invention. Fig. 2 is a front elevation of the boiler. Fig. 3 is a section of the induction and mixing device. Figs. 4 and 5 are side elevations of the elbow containing the mixing head.

The invention is applied to a return tube boiler 10 which may be of any suitable or usual construction and comprises a firebox 11 over a grate 12. A coil of pipe 13 extends transversely across the chamber under the boiler in back of the pre-heated air passing to the induction devices 16 hereinafter described, which deliver steam and air to the combustion chamber over the fire-bed. One end 14 of this coil outside of the furnace is open to admit air to the coil. The other end is connected to a pipe 15 which extends across the front of the furnace to deliver heated air to the mixing and induction devices 16.

Any desired number of induction devices may be used, and they are similar in construction.

Each of said devices comprises an elbow having a branch 17 which is connected to a branch 15^a of the pipe 15 so heated air can be drawn into the elbow. The other branch 19 of the elbow is connected to a pipe 20 which extends through the front wall of the furnace to deliver a mixture of hot air and steam into the firebox above the grate to burn the volatile matter in suspension. A pipe 22, which is connected to receive steam from the boiler, extends into the elbow coaxially with the discharge branch 19, and supports a mixing head or member 21. This head is screw-threaded to the inner end of pipe 22 and is supported thereby in the elbow. A nozzle 24, with a small port 25 to discharge steam in the form of a small jet, is secured in a wall 21^a forming the end of the head 21 which is adjacent the inner end of pipe 22. The inner end of the head 21 is hollow to form a mixing chamber 26 coaxial with the discharge-branch 19 of the elbow. The nozzle 24 is disposed at the inner end of the chamber 26 and the outer end of this chamber is open to direct the fluid through the discharge branch and into pipe 20. An oblique port 27 leads from the outside of the outer portion of the head to the inner end of the mixing chamber 26 and adjacent the nozzle 24. A conical spreader 28, coaxial with the duct 25 in the nozzle 24, is secured in a member 30 which has a reversely cone-shaped inner end 31. Member 30 is connected to and supported in the head by ribs 32. The portion 33 of the discharge branch of the elbow is conoidal or constricted. The head 21 is smaller than the discharge branch 19 of the elbow to provide an annular space or passage 19^a around the head and through which heated air will be drawn by the stream of mixed air and steam discharged under pressure from the mixing chamber 26 in the head. This exemplifies a device in which there is a double induction of heated air to the stream, heated air being first drawn into the mixing chamber 26 through port 27 where the air and steam are impinged against spreader 28, so they will be mixed, and the discharge of the mixed air and steam from the open end of chamber 26, which serves, in effect, as a nozzle, draws air through passage 19^a to mix an additional volume of heated air to the mixture from the head 26, so that sufficient oxygen will be delivered to the firebox for complete combustion of the fuel. By adjusting the head longitudinally within the restricted or conoidal portion 33 of the discharge branch of the elbow, the effective area of the air induction space between the head and the elbow can 55

be varied to regulate the volume of air to meet varying conditions in furnaces or in furnaces of different types. A set screw 34 is threaded to a boss 35 on the elbow through which pipe 22 is 5 slideable and is adapted to lock the pipe to hold the head in its desired or adjusted position in the discharge branch 19 of the elbow. For convenience in mounting and removal of the mixing elbow, branch 17 of the elbow is split as at 10 36 and provided with lugs 37 for a bolt 38 which is adapted to clamp the elbow around one end of pipe 15^a. The other branch of the elbow is provided with similar clamping means for pipe 20.

To obtain practically perfect combustion of coal, black smoke is usually caused by insufficient air in the furnace. Air is brought in through the grates. The oxygen in the air combines with the carbon from the coal in the approximate proportion of two parts of oxygen to one part of 15 carbon. So long as the supply of air is sufficient and well distributed to obtain a proper mixture, a fairly smokeless fire is the result. When this is prevented by too much coal over the grate, there will be incomplete combustion with a resultant dull fire and the emission of black smoke. To produce practically perfect combustion, it is necessary, not only to burn the carbon in the coal, but also the volatile gases. The various 20 proportions of the constituents of coal vary widely as to its fuel value in coal derived from different seams from different sections of the country. To achieve practically perfect combustion, it is necessary to burn the fuel and gases in the furnace. The combustion resulting 25 from air entering the bottom of the fuel bed forms carbon dioxide from the chemical combination of the carbon of the coal and the oxygen of the air. The decomposition of the carbon dioxide to carbon monoxide results as the former 30 is brought into contact with more incandescent carbon and the combustion of the volatile matter to form the various hydrocarbon gases. The recombination of the carbon monoxide with excess oxygen at the top of the fire again forms 35 carbon dioxide and completes the combustion of the volatile matter. To obtain substantially perfect combustion, the temperature of the furnace must be kept sufficiently high to give quick combustion, the flame must have enough time in the 40 air, so that combustion can be completed before it reaches the boiler tubes, and the air, and gas should be thoroughly mixed for complete combustion, which usually occurs in the firebox of the furnace.

50 In practice it has been found that practically perfect combustion may be obtained and smoke prevented when the volatile gases and separated free carbon are brought into intimate contact with the proper quantity of air and maintained 55 at a temperature above the ignition point until oxidation is complete before they are brought into contact with the heat absorbing surfaces of the boiler. Mere excess of air will not effect smokeless combustion, even if the gases and air are thoroughly mixed, if the temperature is prematurely reduced below that necessary for combustion by contact with the heat absorbing surfaces of the boiler.

55 In operation, the steam discharged from the 60 nozzle 24 into the mixing chamber 26 will draw heated air through the heating coil 13 and pipe 15 into the elbow. A portion of the hot air will be drawn into the mixing chamber 26 through port 27, and in said chamber it will be intimately 65 mixed with the steam, the spreader 28 acting as

a baffle to assist in the mixing. The stream of mixed steam and air discharged from the mixing chamber into the discharge branch 19 of the elbow will draw air through the annular passage 19^a around the head. After the second induction of heated air, the mixture will pass from the elbow into pipe 29 and to the firebox. The volume of air added to the stream on the second induction may be varied to adapt the device for different conditions by adjustment of the head 10 to and from the constricted portion 33 of the elbow. The latter acts as an induction nozzle. Pipe 22 can be adjusted from the outside of the elbow to shift head 21 to and from the constricted portion 33. This makes it possible to deliver 15 the necessary volume of hot air and steam to the firebox to produce substantially perfect combustion. The integral clamps at the ends of the branches of the elbow make it possible to quickly install and remove the device whenever necessary. While the invention has been illustrated with a return flue boiler, it is adapted for use with boilers of any of the different well-known types.

The invention exemplifies devices by which a 25 mixture of hot air and steam, in proper quantity and maintained at a temperature above the ignition point, is brought into intimate contact with the volatile gases and separated free carbon to complete oxidation thereof before they are 30 brought into contact with the heat-absorbing surfaces of the boiler; in which a sufficient amount of air for perfect combustion of the volatile gases is delivered to the firebox to produce the aggregate mixture of air and combustible 35 at a temperature which is sufficiently high to complete oxidation of the volatile combustible. The invention also exemplifies a device in which there is an initial induction of hot air to the steam from the jet and a second induction of hot 40 air to the mixed steam and hot air, which is simple in construction, and efficient in operation; also a device in which the nozzle is adjustable relatively to the constricted discharge of the elbow to vary the suction to meet the requirements of different furnaces; also a construction in which the mixing occurs in an elbow 45 which muffles the noise produced by the jet.

The invention is not to be understood as restricted to the details set forth, since these may 50 be modified within the scope of the appended claims, without departing from the spirit and scope of the invention.

Having thus described the invention, what we claim as new and desire to secure by Letters 55 Patent, is:

1. As a new article of manufacture, a device for delivering hot air and steam into the firebox of a heating apparatus for increasing combustion and abating smoke, comprising an elbow 60 having an inlet branch for receiving hot air and a branch extending substantially at right angles to the inlet branch and adapted to discharge into the firebox, an elongated head disposed in the bent portion of the elbow and arranged so that it is axially aligned with, and one end thereof extends into, the discharge branch of said elbow, a nozzle in the central portion of the head, and a pipe for delivering steam to the nozzle extending through the bent portion of the 70 elbow and connected to the other end of the head, said head being provided at said one end thereof with a mixing chamber into which the nozzle discharges and with a discharge opening for the chamber aligned with and facing in the 75

direction of the discharge branch of the elbow, said head also being provided with an angular induction port in the side portion adjacent to the inlet branch for admitting hot air to the chamber
5 for admixture with the steam from the nozzle and having said one end thereof spaced from the side wall of the discharge branch of the elbow to form an air passage around the head through which hot air will be drawn into mixed relation
10 with the mixed air and steam emanating from the mixing chamber via the discharge opening.

2. As a new article of manufacture, a device for delivering hot air and steam into the firebox of a heating apparatus for increasing combustion and abating smoke, comprising an elbow having an inlet branch for receiving heated air and a branch at substantially right angles to the inlet branch adapted to discharge into the firebox provided with a tapered outer end, an elongated head disposed in the bent portion of the elbow and arranged so that it is axially aligned with, and one end thereof extends into, the discharge branch of said elbow, a nozzle in the central portion of the head, a pipe for delivering steam to the nozzle extending through an opening in the bent portion of the elbow and

connected to the other end of the head, said head being provided at said one end thereof with a mixing chamber into which the nozzle discharges and with a discharge opening for the chamber aligned with and facing in the direction of the discharge branch of the elbow, said head also being provided with an angular induction port in the side portion adjacent to the inlet branch for admitting hot air to the chamber for admixture with the steam from the nozzle and having said one end thereof spaced from the side wall of the discharge branch of the elbow to form an air passage around the head through which hot air will be drawn into mixed relation with the mixed air and steam emanating from the mixing chamber via the discharge opening, and means associated with the part of the bent portion of the elbow having the opening through which the pipe extends for supporting the pipe so that it is slidable axially of the discharge 15 branch of the elbow in order to vary the position of the head with respect to the tapered outer end of the discharge branch and thus regulate the size of the air passage around the head.
